DESIGN FOR AN UNDERGROUND MAUSOLEUM

Pasher W. Watson, Jr., Selbyville, Del.

Application August 10, 1937, Serial No. 70,977

Term of patent 14 years

To all whom it may concern:

Be it known that I, Pasher W. Watson, Jr., a citizen of the United States, residing at Selbyville, in the county of Sussex and State of Delaware, have invented a new, original, and ornamental Design for an Underground Mausoleum, of which the following is a specification, reference being had to the accompanying drawing forming part thereof.

I claim:

The ornamental design for an underground mausoleum, as shown.
